(51) **LOC (10) Cl.** 24-02

CLAIM

(52) **U.S. Cl.**

We claim the ornamental design for a handheld oral irrigator, as shown and described.

USPC **D24/111**

DESCRIPTION

(58) **Field of Classification Search**

FIG. 1 is a front isometric view of a handheld oral irrigator. FIG. 2 is a rear isometric view of the handheld oral irrigator of FIG. 1.

USPC D24/111, 112, 152; D4/101, 138
CPC A61C 17/02; A61C 17/0202; A61C 17/0214; A61C 17/028; A46B 2200/1066

FIG. 3 is a front elevation view of the handheld oral irrigator of FIG. 1.

See application file for complete search history.

FIG. 4 is a rear elevation view of the handheld oral irrigator of FIG. 1.

(56) **References Cited**

FIG. 5 is a right side elevation view of the handheld oral irrigator of FIG. 1.

U.S. PATENT DOCUMENTS

FIG. 6 is a left side elevation view of the handheld oral irrigator of FIG. 1.

555,588 A 3/1896 Spencer
1,278,225 A 9/1918 Schamberg
1,464,419 A 8/1923 Gill
1,498,267 A 6/1924 Hachman
1,650,686 A 11/1927 Binks

FIG. 7 is an enlarged top plan view of the handheld oral irrigator of FIG. 1; and,

(Continued)

FIG. 8 is an enlarged bottom plan view of the handheld oral irrigator of FIG. 1.

The broken lines in the drawings illustration portions of the handheld oral irrigator, which form no part of the claimed design.

1 Claim, 8 Drawing Sheets

Related U.S. Application Data

12/709,677, filed on Feb. 22, 2010, now Pat. No. 8,403,665, which is a continuation of application No. 11/483,376, filed on Jul. 7, 2006, now Pat. No. 7,670,141.
